UNITED STATES PATENT OFFICE.

COLUMBUS MCKIBBEN, OF ARANSAS PASS, TEXAS.

BASCULE-BRIDGE.

1,128,478.

Specification of Letters Patent. Patented Feb. 16, 1915.

Application filed January 6, 1914. Serial No. 810,678.

To all whom it may concern:

Be it known that I, COLUMBUS MCKIBBEN, a citizen of the United States, residing at Aransas Pass, in the county of San Patricio 5 and State of Texas, have invented new and useful Improvements in Bascule-Bridges, of which the following is a specification.

This invention relates to improvements in draw bridges, especially bridges of the 10 rocking bascule type in which the movable draw or span is provided at one end with a segmental part adapted to rest and roll upon a stationary supporting surface and in which the segmental pivoting part is 15 provided with a counter weight, spaced from the inner edge of the draw or span and employed to counter balance the same and hence facilitate the raising and lowering of the draw span, the object of the invention 20 being to effect an improvement in bridges of this type by providing a shiftable weight and a supporting guide therefor, which guide is arranged in the angle between the counter balancing weight and the inner end 25 of the draw span and which serves to direct the shiftable weight across the pivotal center of the span, the weight being actuated by its own gravity and controlled by the movement of the span so that the said shiftable weight is caused to assist materially 30 both in the raising and lowering of the draw span, the invention consisting in the construction, combination and arrangement of devices hereinafter described and claimed.

In the accompanying drawings:—Figure 35 1 is a side elevation of a portion of the shoreward end of a bridge span in open position and provided with my improved movable weight, the bridge span being 40 shown in raised position in full lines and indicated in lowered position in dotted lines. Fig. 2 is a transverse sectional view of the bridge on the plane indicated by the line a—c of Fig. 1, and showing the draw span, 45 its supports and operating mechanism in end elevation. Fig. 3 is a detail vertical longitudinal sectional view through the center of one of the supporting guides. Fig. 4 is a detail perspective view of one of 50 the supporting guides.

The shoreward end of the bridge span is indicated at 1, the pivoting segments at 3, the supports on which the said pivoting segments roll are indicated at 3 on the 55 piers 4 and the counter balancing weights are indicated at 5. The said supporting

segments are interposed between the inner end of the draw span and the counter balancing weights and are provided with bars 6 which are at right angles to the center 60 radii of the supporting segments. The draw span is raised and lowered by gears 7 which are driven by suitable motors 8 and engage 65 interiorly toothed segmental members 9 which are concentric with the pivotal axes 65 of the supporting, pivoting and rolling segments 2 said pivotal axes being indicated at 10.

In accordance with my invention I provide supporting guides 11 which are here 70 shown as tubular in form and which are secured on the bars 6 and extend from the shoreward end of the draw span to the 75 weights 5. The ends of the said supporting guides are closed as at 12 and are provided with cushions or bumpers 13. In each supporting guide a spherical weight 14 is mounted for longitudinal movement the 80 said weights being movable by their own gravity and by the rocking movement of the 85 draw span from end to end of the said supporting guides. Hence when the draw span is in closed, lowered position, the weights 14 are at the ends of the supporting guides 90 next the draw span and add their weight to 95 the latter. As the draw span is raised, the weights 14, as soon as the span has been moved through about 45° and the supporting guides 11 reaching a substantially level position begin to move from the ends of the 100 supporting guides next to the draw span and reach a position substantially at the pivotal axes of the rocking supports 2 and as the draw span continues to rise the said weights 14 move outwardly on the supporting guides 11 and reach the ends thereof next the counter balancing weights 5 and hence materially assist in the final elevating movement of the draw span. When the draw span is lowered the weights 14 move 105 toward the same hence materially assist in the final lowering movement thereof, the said weights 14 being movable across the pivotal axis of the draw span.

Under some conditions, as for instance 110 when the wind is blowing in such direction as to materially assist in the lifting of the draw span it is desirable to prevent the weights 14 from moving past the pivotal axis of the draw span and to enable the 115 weights to be thus arrested I provide stops 15 which are here shown as pins that are

adapted to be placed in openings with which the tubular supporting guides 11 are provided, so as to cause the said stop pins to extend across said tubular supporting guides

5 and to bear against the weights 14.

While I have herein shown and described a preferred form of my invention I would have it understood that changes may be made in the form, proportion and construction of the several parts without departing from the spirit of the invention and within the scope of the appended claims.

Having thus described my invention, I claim:—

15 1. In a bascule bridge a draw span, a rolling support therefor at the shoreward end of the span, a counter balancing weight for the draw span and arranged on the shoreward side of the rolling support and at an

20 angle to the said span, a supporting guide arranged in the angle between the counter balancing weight and the draw span and a movable weight in said supporting guide.

25 2. In a bascule bridge a draw span, a rolling support therefor at the shoreward end of the span, a counter balancing weight for the draw span and arranged on the shoreward side of the rolling support and at an angle to the said span, a supporting guide

30 arranged in the angle between the counter balancing weight and the draw span and extending from the weight in said support-

ing guide, the said supporting guide being tubular and a spherical movable weight arranged for movement in the bore of the said 35 supporting guide.

3. In a bascule bridge a draw span, a rolling support therefor at the shoreward end of the span, a counter balancing weight for the draw span and arranged on the shoreward side of the rolling support and at an angle to the said span, a supporting guide arranged in the angle between the counter balancing weight and the draw span, a movable weight in said supporting guide, and 45 buffers at the ends of the said supporting guide.

4. In a bascule bridge a draw span, a rolling support therefor at the shoreward end of the span, a counter balancing weight for 50 the draw span and arranged on the shoreward side of the rolling support and at an angle to the said span, a supporting guide arranged in the angle between the counter balancing weight and the draw span, a movable weight in said supporting guide, and means to limit the extent of movement of the said movable weight.

In testimony whereof I affix my signature in presence of two witnesses.

COLUMBUS MCKIBBEN.
